FUR DRYING RACK

Leon J. Colin, Tarentum, Pa.

Application December 7, 1936, Serial No. 114,538

4 Claims. (Cl. 211—13)

This invention relates to improvements in drying racks, and more particularly to a portable rack for use both in the drying of skins stretched upon pelting boards and also for the displaying 5 of marketable furs.

Heretofore, in preparing furs for market, after the animals had been slaughtered and pelted, the pelts which were turned inside out and stretched over pelting boards were then placed 10 in a drying room for the desired length of time to thoroughly dry the skins.

The general practice was to convey the pelting boards into the drying room and then to suspend the pelting boards from overhead wires. This 15 necessitated frequent handling of the pelting boards and not only increased the cost of preparing the furs for market, but also losses were frequently occasioned by improperly spacing the pelting boards suspended from the wires with the 20 result that the boards would come in contact one with the other, and the skins burned at the point of contact.

The primary object of this invention is to provide a portable rack for holding skins during the 25 drying thereof which will not only eliminate, to a large extent, the handling of the pelting boards upon which the skins are stretched, but which will positively prevent the skins from coming in contact with each other during the drying operation and consequently, prevent the burning of 30 the skins and on which the skins are supported in such a manner that the legs and feet fall away from the body of the skin and danger of burning of the skins adjacent the legs is eliminated.

Another object is to provide a knockdown portable drying rack which can be readily assembled and dismantled, is economical to manufacture, simple in construction, and convenient to use 40 since it can be readily placed in the most advantageous position for filling and then moved without any rehandling of the skins into the drying room.

These and other objects of the invention, which 45 will hereinafter be made readily apparent to those skilled in this particular art, are accomplished by means of this invention, one embodiment of which is described in the following specification and illustrated in the accompanying drawing, wherein:

Figure 1 is a view in perspective of a fur drying rack made in accordance with my invention and illustrating how the pelting boards are supported 50 thereon;

Fig. 2 is a sectional view taken on line II—II of Fig. 1; and

Fig. 3 is a view in perspective of the means for holding the pelting boards in proper position on the rack and having a portion thereof broken 5 away for convenience of illustration.

My improved knockdown rack for drying skins and displaying furs comprises a base or truck formed of opposed side members 10 which are provided with casters or wheels 11 to permit the 10 rack to be moved readily from place to place. In assembling the rack, the side members 10 are arranged in parallel spaced relation and are held in such relationship by opposed rectangular spaced frames 12 which span the space between 15 the side members 10 and to which they are secured by bolts 13. The frames 12 are inclined relative to the side members 10 and have their upper edges bearing against beveled or sloped faces of blocks 14 carried by a center strip 15 20 to which the frames are secured by bolts 16. A member 17 having a groove or trough 18 forming a tray for supporting the lower ends of the pelting boards over which the skins to be dried are adapted to be stretched, is secured to the sides 12a of each of the frames 12 by bolts 20 and, in order that the rack may be used to dry skins of animals having a wide range in size and, consequently, carry pelting boards of different lengths, the sides 12a are each provided with a series 30 of spaced openings 21 for receiving the bolts 20.

When the rack is to be used in drying skins, it is preferably placed in a position convenient to the pelter who removes the skin from the carcass and stretches it over the pelting board. As 35 soon as the skin has been attached to the pelting board 19, the lower end of the board is placed in the trough 18 on one of the inclined frames 12 in such a way that the legs and feet on the skins fall away from the body thereof toward the center 40 of the rack with the upper end of the board bearing against the top member 12b of the frame 12.

When one of the frames 12 of the rack has been filled with pelting boards 19 having the skins to be dried attached thereto, a member 22 having a series of spaced cleats 23 projecting from one side thereof is placed over the frame in such a manner that the cleats 23 project inwardly between adjacent boards on the frame 50 and not only space the pelting boards so as to secure the proper distance between the skins carried thereby, but also prevent lateral movement of those boards. The cleats 23 are of such length that when the member 22 is placed on the 55

frame 12, the ends thereof lie substantially in the same plane as the outer face of the top member 12b.

- In order that the member 22 may be readily positioned on and removed from the frames 12, a notch 24 is provided at each end thereof which is adapted to slip over a headed pin 25 projecting outwardly from a block 26 attached to each of the members 12a adjacent the top of each frame 12. After the members 22 have been positioned over each of the frames 12 the rack is then moved into the drying room and the skins dried while the pelting boards are retained in place on the rack.
- When it is desired to use my improved portable rack for the displaying of marketable furs, the members 17 are removed from the frames 12 and wires or slats are stretched across the frames between the members 12a for supporting the furs which are attached to hooks 27 on the underside of the members 22.

From the foregoing description, it is apparent that I have provided a knockdown rack on which the skins can be dried without undue handling and in which the skins are properly spaced apart and held out of contact one with another and that excessive handling of the skins on the pelting boards is eliminated.

While I have illustrated my improved rack as being made of wood, it is understood that I do not desire to be limited to that material alone and that the rack may be made of any suitable material without departing from my invention, and it is further understood that certain other changes, modifications, omissions, and substitutions may be made therein without departing from the spirit of my invention or the scope of the appended claims.

What I claim as new and desire to secure by Letters Patent is:

1. A drying rack comprising a base, inclined

drying frames supported on said base, a trough adjustably mounted on each of said frames for receiving the lower ends of a series of pelting boards, and a spacing member secured to each of said frames adjacent the top thereof and adapted to engage the outer surfaces of said pelting boards for retaining them in place on said frame.

2. A drying rack comprising a base, frames carried by said base, said frames being secured together at their upper ends and spaced apart at the base to provide inclined supports, a trough adjustably mounted on each of said inclined frames for receiving the lower end of a series of pelting boards, the upper ends of which rest against the top of each said frame, and a member attached to each of said frames adapted to engage the outer surfaces of said boards and having means for spacing and holding the pelting boards thereon.

3. A drying rack comprising a base, frames carried by said base, said frames being secured together at their upper ends and spaced apart at the base to provide inclined supports, a trough adjustably mounted on each of said inclined frames for receiving the lower end of a series of pelting boards, a member attached to each of said frames for engaging the tops of said pelting boards, and means on each said member for laterally spacing the pelting boards.

4. A drying rack comprising a base, a pair of inclined drying frames carried by said base, a pelting board receiving tray adjustably mounted on each frame, and a member mounted on each of said frames for engaging the outer surfaces of the pelting boards and having a series of projections thereon adapted to project between adjacent pelting boards to space the same and hold the boards against lateral movement relative to said frame.
